UNITED STATES PATENT OFFICE.

JULIUS GLOWACKI, OF SOUTH BOSTON, MASSACHUSETTS.

SAND AND ROCK SEPARATOR.

Application filed May 11, 1928. Serial No. 277,062.

This invention relates to improvements in separators, particularly to a sand and stone or rock separator, and it is the principal object of my invention to provide a motor operated separator of this type in which the material scooped from the ground is broken up within a hopper and then transferred to a screen and sifted therein, whereby provisions are made to remove the rocks and stones not 5 passing through the sieve or screen during 10 the sifting operation at the end of each operation.

Another object of my invention is the provision of a sand and stone separator in which 15 the screen is submitted to a shaking motion and the screen of which allows a lowering of its rear part to deliver larger bodies not passing the screen meshes to a shuttle or chute for removal.

20 A further object of my invention is the provision of a motor operated sand and rock separator equipped with novel and improved steering and braking means.

A still further object of my invention is 25 the provision of a motor operated sifter for sand and gravel etc., of comparatively simple and inexpensive construction yet efficient in operation.

These and other objects and advantages of 30 my invention will become more fully known as the description thereof proceeds, and will then be specifically defined in the appended claims.

In the accompanying drawings forming a 35 material part of this disclosure:—

Fig. 1 is a side view of a sand and rock separator constructed according to my invention.

Fig. 2 is a top plan view of the same.

40 Fig. 3 is a section on line 3—3 of Figure 2.

Fig. 4 is a side elevation of the separator, partly in section on line 4—4 of Figure 2.

Fig. 5 is a fragmentary longitudinal section on line 5—5 of Figure 6.

45 Fig. 6 is a fragmentary top plan view partly in section on line 6—6 of Figure 5, some parts being omitted for the sake of clearer illustration.

Fig. 7 is a section on line 7—7 of Figure 4.

50 Fig. 8 is a top plan view on the steering mechanism, partly in section on line 8—8 of Figure 4.

Fig. 9 is a rear view of the steering mechanism, partly in section on line 9—9 of Figure 1.

Fig. 10 is a section on line 10—10 of Figure 8.

As illustrated, the separator comprises a box 10, supported on a frame 11 carrying the axle 12 for the larger rear wheels 13 and the 60 axle 14 for the smaller front wheels 15.

On one side the frame carries a seat 16 for the operator with which a foot rest 17 is combined, while under the seat a tool box or chest 18, and beside the driver's seat a switch box 65 19 are provided.

A scoop 20 has its operating bars 21 pivotally secured, as at 22 to frame 11 and formed into toothed segments 23, in mesh with gears 24 on a shaft 25, which also carries a pulley 70 26 over which a belt 27 runs, which is also guided over a pulley 28 on a shaft 29.

A chute or hopper 30 is arranged at the front end of box 10 and adapted to receive the material from scoop 20. The bottom of 75 the chute is open and can be closed partially or entirely by means of the displaceable side wall 31 which carries a rack 32 on its outside in mesh with a gear 33 on a shaft 34 which carries a hand wheel 35 at its outer end 80 (Fig. 7).

Within the hopper a longitudinally extending shaft 36 is journalled which carries a plurality of stirrer blades 37 arranged in spaced juxtaposition within the hopper 30. 85

The shaft 36 carries outside of the hopper a pulley 38 over which a belt 39 is guided and also over a pulley on a transverse shaft 40.

An endless belt 41 having a plurality of frames 42 on its upper face is guided over a 90 pulley 43 on shaft 40 which carries also a pulley 44 over which a belt 45 is guided, which is also guided over a pulley 46 on shaft 36 to operate the stirrer within the hopper.

The belt 41 is also guided over a pulley 47 95 on a shaft 48 journalled in suitable bearings on the box 10. Suitable guides 49 are provided at certain intervals and suitably arranged to hold the belt taut.

The box 10 in its rear part has a depending body 50 attached to its bottom part and above the same a screen 51 is suspended at its rear end by means of cables 52 guided over suitable rollers 53 on a shaft 54. To the front part or end wall of the screen an extension 100 55 is attached which rests on a roller 56. An arm 57 is attached at one end to an eye on the end wall of the screen and at its opposite end to a link 58 the other end of which is eccentrically secured to the side face of a 105 59.

disc 59 on a shaft 60 carrying also a pulley 61 over which a belt 62 is guided which is also guided over pulley 47 on shaft 48.

As shown in Figures 1, 2, 3, and 4, at the rear part of the box transversely disposed thereto a shuttle or chute 63 is suspended by hangers 64 from the box and has its bottom part slanting towards one side for the reception of the larger bodies, stones, etc., remaining in the screen after the screening operation, and the shaft 54 carries outside of the box 10 a hand wheel 65, while a ratchet wheel 66 on said shaft is engaged by a pawl 67.

On a transversely arranged beam 68, a motor 69 is located, the shaft 70 of which carries a gear 71 in mesh with a large gear 72 on a shaft 73 which carries also a gear 74, in mesh with a smaller gear 75 on shaft 29. Gear 75 is also in mesh with a gear 76 on a shaft 77 which also carries a pulley 78 over which a belt 79 is guided, also guided over a pulley 80 on a shaft 81. Double pulley 78 carries also a belt 82 guided over a pulley 83 on a shaft 84, over this double pulley 83 also a belt 85 is guided running over a pulley 86 on the rear axle 12.

The motor is connected to a suitable source of electricity by means of a cable 87 adapted to be wound upon a drum 88 on a vertical shaft 89 journalled in a suitable bearing on a post 90, and a bearing 91 on box 10.

The lower end of shaft 89 carries a bevel gear 92 in mesh with a bevel gear 93 on shaft 81, and a clutch 94 is adapted to be operated by a lever 95.

A suitable brake mechanism is provided, consisting of a brake wheel 96 on shaft 73 over which a band 97 is guided having one of its ends attached to the rear edge of beam 68 while its other end is secured to a loop 98 intermediate the ends of a rod 99 carrying on its outer end a foot pedal 100.

Suitable clutch members 101 are provided on shaft 99 and adapted to be shifted by a clutch shifter 102 while a clutch 103 is adapted to be shifted by means of a shifter 104.

Shaft 73 carries also a pulley 105 over which a belt 106 is guided which is also guided over a pulley 107 on shaft 40.

The steering mechanism for the front wheels 15 on axle 14 comprises a steering rod 108 adapted to be operated by means of a hand wheel 109 in front of the driver's seat 16 and guided in suitable guides 110, 111. This rod carries at its outer end a gear 112 in mesh with a rack 113 sliding in a suitable guide sleeve 114 on a frame bar 115.

The inner end of bar 113 is pivotally attached as at 116, to a lever 117 of the front bar 118 articulated, as at 119, 120 to axle 14.

Snap-hook connections 121 or the like, are provided at the upper, front edge of the hopper 30 adapted to be engaged by similar

connections 121' on the scoop 20 to hold the same securely in its elevated position.

The shaft 36 of the stirrer is set exchangeably in blocks or lugs 122 having suitable depressions for the reception of the reduced ends of the shaft.

Below the drum 88, the shaft 89 thereof is equipped with a disc 123 acting as a friction brake for the drum and cable therein.

The apparatus operates as follows:

As soon as the motor is started to move the machine slowly forward, the scoop 20 will pick up the material and through the gears and belts, and its toothed segment will elevate the material and discharge it into the hopper 30 where it is stirred up to fall upon the endless belt conveyer by which it is transferred onto the screen which will receive a shaking motion by means of the eccentric link 58 on wheel 59. As soon as sufficient stones and rocks have accumulated in the screen, the rear end of the same is lowered to dump these stones and rocks which have not passed through the screen into the chute or shuttle 63 from which the material can readily be removed.

It will be understood that I may make such changes in the construction of my apparatus as come within the scope of the appended claims without departure from the invention as disclosed.

Having thus described my invention, what I claim as new and desire to secure by Letters Patent is:—

1. Separator comprising a wheeled box, means in said box to receive material, means in said receiving means to stir the material, means to scoop the material from the ground and to transfer it to said material receiving means, a screen, means to transport the material from said receiving means to said screen, means for shaking said screen, means for allowing a removal of the screen residue, and a means for operating all of said means from a common motor.

2. Sand and rock separator comprising a wheeled box, a scoop at the front of said box, a hopper, means for depositing the material scooped from the ground into said hopper, stirring means in said hopper, an endless conveyer, means for dumping the material from said hopper onto said conveyer, a screen adapted to receive the material from said conveyer, means for shaking said screen, means for lowering the rear part of said screen, a shuttle into which the stones and rocks not passing through the screen are deposited upon the lowering of the rear part of said screen, gear and belt drives, and a motor connected to said gear and belt drives for operating all of said means.

3. A motor-operated sand and rock separator comprising a wheeled box, a frame therefor, means for steering the front part of the frame, a scoop and a hopper adapted

to be filled with the material from said scoop, a movable wall on said hopper controlling the width of the bottom opening thereof, an endless conveyer belt, a plurality 5 of boxes on said belt, material stirring means in said hopper for stirring and depositing the material scooped into the hopper onto said conveyer, a screen, receiving the material from said conveyer, means for shaking 10 said screen and the material therein intermittently, a shuttle at the rear end of said box below said screen, inclined towards one

side, means for depositing the residue of screening into said shuttle for removal therefrom, a means for steering the apparatus, a gear and belt drive, a motor and connections between said motor and gear and belt drive to operate the scooping, stirring, conveying and screening means.

Signed at So. Boston, in the county of 20 Suffolk and State of Massachusetts, this 25th day of April, A. D. 1928.

JULUS GLOWACKI.
